APPARATUS FOR AUTOMATIC GRINDING

In presently available grinding machines, a manual handwheel is normally connected to the feed system of the machine. This requires a complicated and complex mechanism which has many mating members, thus reducing the overall rigidity of the feed system. The reduction of rigidity of the drive increases the possibility that chatter may occur, for example, whereby damage of the workpiece, which is being ground, would occur. Additionally, the lack of rigidity has an effect on the final size of the workpiece since the spring of the system increases with a reduction in rigidity.

The present invention satisfactorily solves the foregoing problem by utilizing a unique arrangement for the infeed mechanism for a grinding wheel. In the infeed mechanism of the present invention, a relatively small moment arm exists between the axis of the grinding wheel and the axis of the feed screw. This is accomplished by eliminating any requirement for a manual handwheel to control movement of the grinding wheel toward and away from the workpiece. The present invention utilizes an automatic control for movement of the grinding wheel toward and away from the workpiece so that the complicated structure of the handwheel and its connecting means is eliminated.

In presently available grinding machines in which the manual handwheel is disposed at the front of the machine and the feed screw extends rearwardly therefrom beneath the coolant trough, the feed screw must pass through the support structure for the workpiece so that there is interference therebetween. Accordingly, if a different type of support structure is required for the workpiece, substantial modification may be required. In the present invention, the infeed mechanism is mounted only on the rear base of the machine so that it does not have any structure extending forward of the rear base. As a result, the present invention permits any type of support structure for the workpiece to be readily utilized with the rear base, which has the infeed mechanism and the wheelhead supported thereon.

In presently available grinding machines, the grinding wheel is fed into the workpiece at one or more different decreasing feed rates as the final size of the workpiece is approached. The grinding wheel must not be fed into the workpiece the entire distance that it is desired to reduce the workpiece because of the windup or spring in the grinding machine and workpiece system due to the feed force of the grinding wheel since this windup or spring must be removed upon completion of grinding of the workpiece. Therefore, in presently available grinding machines, advancement of the grinding wheel into the workpiece is stopped short of the desired position to which it would be moved to obtain the final desired workpiece size. The grinding wheel is retained in this position for a period of time to finally finish the workpiece as the workpiece and the grinding wheel release their spring or windup due to the grinding wheel no longer exerting a feed force on the workpiece.

In the present invention, the grinding wheel may be continuously fed into the workpiece for the distance required to produce the final size of the workpiece. Then, the grinding wheel is retracted from the workpiece a predetermined distance before tarry or dwell occurs. Thus, when the grinding wheel is retracted from the workpiece, the windup or spring in the workpiece results in the workpiece remaining in engagement with the grinding wheel so that the desired size and finish of the workpiece is obtained. Therefore, the present invention reduces the time required to grind a workpiece and permits better control of the desired size and finish of a workpiece than is presently available.

When utilizing an automatic grinding machine, the grinding wheel is normally advanced from a reference position for its infeed. Since the size of the grinding wheel reduces as wear occurs, it is desirable to be able to compensate for this wear at various times before truing of the grinding wheel is required.

The present invention satisfactorily meets this problem by including means to automatically compensate for wear of the

grinding wheel so as to change the reference position from which the grinding wheel is fed into the workpiece. Therefore more uniformity of the size of the finished workpieces, which are produced by the automatic grinding machine of the present invention, is obtained than has been previously available.

Instead of changing the feed rate of the grinding wheel toward the workpiece at various predetermined distances from the reference position, the feed rate of the grinding wheel toward the workpiece may be controlled by a gage. This gage would stop the final feed rate of the grinding wheel toward the workpiece when the gage indicates that the workpiece is of the desired size. Thus, instead of relying upon predetermined distances from a reference position for obtaining the desired final size of the workpiece, the present invention permits the utilization of a gage for automatically controlling when the final size of the workpiece is reached.

An object of this invention is to provide an apparatus for automatically grinding a plurality of workpieces to substantially the same size.

Another object of this invention is to provide a unique infeed mechanism for a grinding wheel.

Other objects of this invention will be readily perceived from the following description, claims, and drawings.

This invention relates to a mechanism for producing relative movement toward and away from each other between a grinding wheel and a workpiece. The invention includes a feed member adapted to be connected to one of the support means for the workpiece and a wheelhead or the like on which the grinding wheel is supported and fluid-responsive means. Means, which is connected to the feed member and to the fluid-responsive means, moves the feed member both independently of the fluid-responsive means and simultaneously therewith. The fluid-responsive means moves the feed member at a faster rate than the connected means with the connected means being movable with the fluid-responsive means to move the feed member.

This invention also relates to a mechanism for controlling the grinding of a workpiece by a grinding wheel. The mechanism includes means to feed one of the grinding wheel and the workpiece toward the other whereby one of the grinding wheel and the workpiece is a movable member and the other of the grinding wheel and the workpiece is a fixed member. The feed means feeds the movable member for a predetermined distance from a reference position with means to automatically stop feeding by the feed means when the movable member has been advanced toward the fixed member the predetermined distance from the reference position. Means retracts the movable member a predetermined distance after the stop means is actuated with the grinding wheel and the workpiece remaining in engagement with each other in the retracted position of the movable member. The movable member is held at the retracted position for a predetermined period of time by suitable means.

This invention further relates to a mechanism for controlling the grinding of a workpiece by a grinding wheel including means to feed one of the grinding wheel and the workpiece toward the other whereby one of the grinding wheel and the workpiece is a movable member and the other of the grinding wheel and the workpiece is a fixed member. The feed means feeds the movable member from a reference position with means to measure the size of the workpiece being ground. The measuring means has means to reduce the feed rate of the feed means when the workpiece has been reduced to a predetermined size by the grinding wheel as determined by the measuring means. Feeding of the movable member by the feed means is stopped by suitable means when the workpiece has further been reduced by the grinding wheel as determined by the measuring means.

This invention still further relates to a grinding machine including front and rear bases connected to each other with a grinding wheel mounted on the rear base by suitable means for movement relative to the rear base. The front base has work-

piece support means mounted thereon and the grinding wheel is moved toward and away from a workpiece on the workpiece support means by feed means, which is supported only on the rear base.

The attached drawings illustrate a preferred embodiment of the invention, in which:

FIG. 1 is a sectional view, partly in elevation, of the automatic grinding machine of the present invention showing the infeed mechanism;

FIG. 2 is an end elevational view of a portion of the automatic grinding machine of the present invention including the infeed mechanism;

FIG. 3 is a sectional view taken substantially along line 3-3 of FIG. 2;

FIG. 4 is a side elevational view of a portion of the structure of FIG. 2 and taken from the left side of FIG. 2;

FIG. 5 is a side elevational view of the structure of FIG. 2 and taken from the right side of FIG. 2;

FIG. 6 is an enlarged sectional view, partly schematic, of a portion of the structure of FIG. 2 and showing the fluid arrangement for rapid movement of the wheelhead;

FIG. 7 is an enlarged sectional view of a clutch for connecting the feed screw to a motor;

FIG. 8 is a schematic diagram illustrating the logic when the automatic grinding machine is in the manual mode;

FIGS. 9a and 9b are schematic views illustrating the logic of the automatic grinding machine when the automatic grinding machine is in a plunge grind mode;

FIG. 9c is a schematic view illustrating the arrangement of FIGS. 9a and 9b;

FIGS. 10a-10c are schematic views illustrating the logic when the automatic grinding machine of the present invention is in a gage grind mode;

FIG. 10d is a schematic view illustrating the arrangement of FIGS. 10a-10c;

FIGS. 11a-11c are schematic views illustrating the logic when the automatic grinding machine of the present invention is in a pickfeed grind mode; and

FIG. 11d is a schematic view illustrating the arrangement of FIGS. 11a-11c.

Referring to the drawings and particularly FIG. 1, there is shown an automatic grinding machine of the present invention. The automatic grinding machine of the present invention includes a grinding wheel 10, which is rotatably mounted on a wheelhead 11. The wheelhead 11 is adapted to be moved along ways 12 (see FIG. 2) in a rear base 14 of the grinding machine of the present invention.

The grinding wheel 10 is adapted to be advanced into engagement with a workpiece 15, which is mounted between a headstock 16 and a tailstock (not shown), for example. The headstock 16 and the tailstock are supported on a swivel table 17, which is swivel-mounted on a sliding table 18. The sliding table 18 is mounted on ways 19 of a front base 20 for movement transversely to the grinding wheel 10.

The front base 20 and the rear base 14 form the machine base of the present invention. Each of the front and rear bases is readily usable with other bases since the structure supported by each is completely separate.

The infeed mechanism for moving the grinding wheel 10 into and away from grinding engagement with the workpiece 15 includes a feed screw 21, which is connected to the wheelhead 11 through a feed or ball nut 22, a plate 23 (see FIG. 3), and a substantially U-shaped bracket 24. The bracket 24, which is fixedly secured to the wheelhead 11 by screws 25, has the plate 23 secured thereto by screws 26. Since the plate 23 has the ball nut 22 secured thereto by screws 27, the feed screw 21 is connected to the wheelhead 11 for causing movement thereof along the ways 12.

The ball nut 22 comprises a pair of nuts 28 and 29, which are spaced from each other by a spacer 30 that determines the preload on the nuts 28 and 29. The nuts 28 and 29 and the spacer 30 are secured to each other by the screws 27, which also connect the ball nut 22 to the plate 23.

This arrangement allows the feed screw 21 to be rotatably movable relative to the feed nut 22 to transmit its rotation into axial movement of the wheelhead 11. The arrangement also allows axial movement of the wheelhead 11 by the feed screw 21 when it is axially moved by a hydraulic piston 31 (see FIG. 3).

The feed screw 21 is rotatably driven by a stepping motor 32 through a reducing unit 33. One suitable example of the stepping motor 32 is the electric stepping motor sold by Superior Electric Company as Type HS50. One suitable example of the speed-reducing unit 33 is sold by United Shoe Machinery Company as Model HDUC-20-100. It should be understood that the speed-reducing unit 33 may be formed with various ratios of speed reduction depending upon the type of machine upon which the workpiece is to be ground.

The stepping motor 32 is carried on one end of the movable hydraulic piston 31, which is slidably disposed in a chamber 33' (see FIG. 6) within a hydraulic cylinder housing 34. The hydraulic cylinder housing 34 is fixedly secured against movement by being secured to the rear base 14 by ears 35 (see FIG. 2) on the cylinder housing 34 being connected to ears 36 on the rear base 14 by screws 37.

Thus, whenever the hydraulic piston 31 is advanced from the position of FIG. 3, the wheelhead 11 will be moved along the ways 12 so that the grinding wheel is moved toward the workpiece 15. Thus, the hydraulic piston 31 allows a rapid advance of the grinding wheel 10 to a reference position, which is selected by the operator, from which the stepping motor 32 may be employed for advancing the grinding wheel 10 into engagement with the workpiece 15 at the desired feed rate. The stepping motor 32 is secured to the piston 31 through a support 38, which is secured to the end of the piston 31 by screws 39. The stepping motor 32 is fixed to the support 38 by screws 40.

The support 38 carries a pair of cam rollers 41 and 42 on its flange 43. The cam rollers 41 and 42 ride on opposite sides of a rail 44, which is supported by the hydraulic cylinder housing 34. Thus, the cam rollers 41 and 42 and the rail 44 insure that any rotation of the feed screw 21 by the stepping motor 32 is transformed into axial motion of the wheelhead 11 and the grinding wheel 10. Furthermore, the cam rollers 41 and 42 cooperate with the rail 44 to insure that only axial movement of the hydraulic piston 31 occurs when the hydraulic piston 31 is actuated.

In addition to rotation of the feed screw 21 by the stepping motor 32, the feed screw 21 also may be rotated by an AC induction motor 45, which is supported on the rear base 14. The induction motor 45 drives the wheelhead 11 at a more rapid rate than is available with the stepping motor 32. The motor 45 has its output shaft connected through a shaft 45a having flexible couplings therein to a vertically disposed shaft 45b, which is rotatably supported by the base 14, through a worm 45c on the shaft 45a and a worm wheel 45d on the lower end of the shaft 45b. Accordingly, the motor 45 rotates the shaft 45b.

The upper end of the shaft 45b has a bevel gear 46 mounted thereon for meshing with a bevel gear 46a, which is secured to an annular member 46b (see FIG. 7). The member 46b is secured to a member 46c having a thin annular section 46d forming a wall of a recess 46e within the members 46b and 46c. Fluid is supplied to the recess 46e through an annular passage 46f, which is in communication with a source of fluid under pressure, in the member 46b.

The member 46c is mounted in surrounding relationship to a bushing 47, which has splines on its inner surface for cooperation with a splined shaft 48. When fluid is supplied to the recess 46e, the thin annular section 46d is deflected inwardly to grip the bushing 47 and cause rotation of the shaft 48 through the splined connection on the shaft 48 and in the bushing 47.

The splined shaft 48 is formed integral with the feed screw 21 and disposed at one end thereof. Thus, the feed screw 21 is rotated by the motor 45 whenever fluid under pressure is supplied to the recess 46e and the motor 45 is energized.

Whenever there is no fluid pressure in the recess 46e, the torque motor 45 cannot rotate the feed screw 21. However, rotation of the feed screw 21 by the stepping motor 32 can occur and result in the splined shaft 48 rotating without any effect on the drive from the motor 45 since the thin annular section 46d is not gripping the bushing 47. Additionally, the bushing 47 allows axial movement of the feed screw 21 and the splined shaft 48 relative thereto when the wheelhead 11 is advanced by the piston 31.

It should be understood that the logic circuit of the present invention prevents actuation of the motor 45 if the motor 32 is energized and vice versa. Thus, there can be no inadvertent attempt by the motors 32 and 45 to simultaneously drive the feed screw 21.

The actuation of the hydraulic piston 31 is controlled through a suitable fluid system. The system includes a pump 50, which supplies fluid from a reservoir 50', connected to an inlet port of a valve 51, which is controlled by a solenoid 52. When the solenoid 52 is not energized, the valve 51 is disposed in the position shown in FIG. 6 whereby the pump 50 communicates through the valve 51 with a line 53, which leads to a valve 54. The valve 54 is disposed in the position of FIG. 6 when a solenoid 55, which controls the position of the valve 54, is not energized. In the position of the valves 51 and 54 as shown in FIG. 6, the fluid is supplied from the pump 50 to cause retraction of the piston 31 so as to retract the grinding wheel 10 rapidly away from the workpiece 15. This fluid is supplied from the pump 50 through a line 56 to the interior of the housing 34 to act on the piston 31.

When it is desired to advance the grinding wheel 10 toward the workpiece 15, the solenoid 55 is energized whereby the fluid from the pump 50 is supplied through a line 57 to the interior of the hydraulic cylinder housing 34. This acts on the piston 31 to rapidly move the grinding wheel 10 toward the workpiece 15. However, the amount of movement of the piston 31 is such that the grinding wheel 10 is not moved into engagement with the workpiece 15.

As shown in FIG. 6, the piston 31 is beveled at each end. Accordingly, when fluid is supplied through the line 57 to advance the grinding wheel 10 toward the workpiece 15, the fluid passes from the line 57 through a chamber 58 in the housing 34, a line 59, a valve 60, and a line 61. As the piston 31 advances through the chamber 33' in the housing 34 to the right as shown in FIG. 6, the fluid on the right side of the piston 31 exits therefrom through a line 62, a valve 63, and the line 56.

As soon as the solenoid 55 is energized, fluid under pressure is supplied to the line 57 and to the left side of a freely movable piston 69, which is disposed within the chamber 58 in the housing 34. Because the chamber 58 communicates with the line 56 through a line 75, the right side of the piston 69 is exposed to exhaust pressure. Thus, as fluid is applied to the left side of the piston 69, the piston 69 is driven to the right to allow fluid to pass through the lines 59 and 61 to the left side of the piston 31.

As the piston 31 approaches the end of the chamber 33' in the housing 34 in which it is movable, it gradually closes the line 62 causing the wheelhead 11 to be decelerated. After the line 62 is closed by the piston 31, the fluid exits from the chamber 33' through a line 64 into the valve 63. The line 64 communicates with the line 56 through a ball valve 65, which forms part of the valve 63, and is resiliently biased by a spring 66 into engagement with one end of a threaded stud 67. By adjusting the position of the threaded stud 67, the position of the ball valve 65 within housing 68 of the valve 63 is changed. Thus, the position of the threaded stud 67 in the valve housing 68 regulates the final approach rate of movement of the piston 31 as it completes its advance movement.

A control rod 70, which is slidably mounted within the housing 34, has a clamping ring 71 adjustably mounted thereon. The clamping rod 71 is engaged by a member 72, which is carried by the support 38 so as to be movable with the piston 31. Thus, as the piston 31 advances to the right in FIG. 6, the member 72 on the support 38 engages the clamping ring

71 and starts movement of the control rod 70. This moves the rod 70 into the chamber 58 as indicated in dotted lines.

When the piston 31 completes its forward movement, a switch 73, which is carried on the housing 34, has its arm 73' engaged by a pin 74 (see FIG. 4) on the support 38. This indicates to the logic circuit of the present invention that the piston 31 has completed its forward movement and the stepping motor 32 may now be energized.

When it is desired to retract the piston 31 from its forward-most position, the solenoid 55 is deenergized to change the position of the valve 54 to allow fluid to be supplied to the chamber 33' through the line 56 and exhausted from the chamber 33' through the line 57. The fluid initially enters the chamber 33' by flowing from the line 56 past the ball valve 65 in the valve housing 68 into the line 64. This results in the fluid acting on the beveled portion of the piston 31.

As the piston 31 is retracted by the pressurized fluid, the line 62 is uncovered. As a result, the fluid flow past the ball valve 65 and through the line 64 becomes negligible.

As the piston 31 retracts, the fluid flows from the chamber 33' through the line 61, the valve 60, and the line 59 to the chamber 58 and then through the line 57. At this time, the piston 69 is not disposed in the solid line position of FIG. 6. However, the chamber 58, which has the piston 69 therein, is receiving fluid from the line 56 through the line 75, which provides communication from the line 56 to the chamber 58. Therefore, fluid pressure acts on the right side of the piston 69 to cause it to move the control rod 70 to the left. The amount of movement of the control rod 70 by the piston 69 is limited by the clamping ring 71 engaging the member 72 on the support 38. Since the member 72 is moving with the piston 31, the piston 69 cannot move the control rod 70 any further than the piston 31 has moved.

As the piston 31 retracts, the control rod 70 is continued to be moved by the piston 69 until the piston 69 blocks the line 59 from communication with the line 57. When this occurs, fluid exhausting from the chamber 33' through the line 61 is stopped so that retraction of the piston 31 by fluid entering the chamber 33' from the line 56 is stopped. Therefore, as soon as the piston 69 blocks the line 59 from communicating with the line 57, retraction of the piston 31 is stopped.

The piston 69 has its left end beveled so that the flow from the line 59 to the line 57 is cut off smoothly. Thus, a smooth deceleration of the piston 31 occurs.

When the retraction of the piston 31 is stopped, a switch 76, which is carried by the housing 34, is actuated through having its arm 77 engaged by a clamping ring 78; the ring 78 is mounted on the control rod 70 on the opposite side of the member 72 from the ring 71. The actuation of the switch 76 provides a signal to the logic circuit of the grinding machine to indicate that retraction of the piston 31 has stopped. This results in energization of the solenoid 52 to move the valve 51 to a position in which the fluid on each side of the piston 31 is trapped therein so as to prevent any further movement of the piston 31.

Whenever it is desired to reduce the amount of retraction of the piston 31, it is only necessary to move the clamping ring 71 to the right. As a result, the control rod 70 will not be moved by the piston 31 as far to the right during its advancement. Thus, the piston 69 does not have to move as far to the left to block the line 59 from communication with the line 57 during retraction.

When it is desired to retract the piston 31 the complete length of the chamber 33', it is necessary to prevent fluid flow from the line 56 into the chamber 58 through the line 75. To accomplish this, the line 75 has a plug 79 therein to cause the fluid flowing through the line 75 to have to pass through a valve 80, which is controlled by a solenoid 81. During normal operations, the solenoid 81 is deenergized to allow flow through the line 75.

When it is desired to retract the piston 31 the entire length of the chamber 33', the solenoid 81 is energized whereby the line 75 no longer provides communication from the line 56 to

the chamber 58. As a result, the piston 69 is not moved by fluid pressure to block communication between the lines 57 and 59.

Therefore, fluid continues to escape from the chamber 33' through the line 61, the valve 60, and the line 59 to the line 57 until the line 61 is blocked by the piston 31. When the line 61 is blocked, a line 82, which communicates with the line 59 through a passage in housing 84 of the valve 60 in which a ball valve 83 is disposed, has fluid flowing therethrough to the line 59. The position of the ball valve 83, which is resiliently biased against one end of a threaded stud 85 by a spring 86, is adjusted by the threaded stud 85 in the housing 84 to regulate the final approach rate of movement of the piston 31. It should be noted that the left side of the piston 31 is beveled in the same manner as the right side to aid in deceleration of the piston 31 during full retraction.

When the piston 31 is completely retracted, this position of the piston 31 is indicated to the logic circuit of the present invention through actuating a switch 87 (see FIG. 4), which is supported on the housing 34, by having its arm 88 engaged by the pin 74 on the support 38, which is carried with the piston 31. This allows the logic circuit to proceed with the additional operations of the grinding process.

In order to limit rearward movement of the feed screw 21, a limit switch 89 (see FIG. 2) is mounted on the support 38 by a bracket 90. When a roller 91 on an arm 92 of the limit switch 89 is engaged by a setscrew 93 on the wheelhead 11, the limit switch 89 indicates this to the logic circuit and stops further rearward movement of the stepping motor 32 or the motor 45. Accordingly, neither the stepping motor 32 nor the motor 45 can be energized to cause further rearward movement of the feed screw 21 once the switch 89 has been actuated.

Forward movement of the feed screw 21 is stopped by a limit switch 94, which is mounted on the support 38 by a bracket 95. When a roller 96 on an arm 97 of the switch 94 is engaged by a block 97' on a rod 98, which is supported by the wheelhead 11, the switch 94 is actuated to indicate to the logic circuit that forward movement of the feed screw 21 must be stopped. Accordingly, neither the stepping motor nor the motor 45 can be energized to cause further forward movement of the feed screw 21 once the switch 94 has been actuated. The rod 98, which is supported within passages in ears 99 and 99a (see FIG. 5) on a flange 99b of the bracket 95, is actuated by the wheelhead 11 when the feed screw 21 has been advanced the permissible maximum by the stepping motor 32 or the motor 45. When the rod 98 is moved by the wheelhead 11, the block on the rod 98 actuates the switch 94.

It should be understood that a spring 99c, which surrounds the rod 98 between the ears 99 and 99a, continuously urges the block 97' on the rod 98 away from the roller 96. Thus, after the switch 94 is actuated, rearward movement of the wheelhead 11 results in the block 97' on the rod 98 ceasing to engage the roller 96 due to the force of the spring 99c.

The infeed mechanism of the present invention may be readily utilized for plunge grinding, gage grinding, or pickfeed grinding. The logic of the grinding machine permits utilization of these various cycles automatically. The operation of the grinding machine of the present invention will be described through schematic diagrams to indicate the logic circuits whereby the various automatic grinding cycles may be carried out.

Referring to FIG. 8, there is shown a schematic block diagram of the logic circuit employed in a manual mode whereby a desired or selected reference position of the stepping motor 32 for each cycle will be determined. After a manual select button 101 is pushed to select the manual mode, actuation of a cycle start button 100 advances the grinding wheel 10 rapidly toward the workpiece 15 through causing fluid to be supplied to the chamber 33' to act on the piston 31 to advance the piston 31. Thus, actuation of the button 100 causes deenergization of the solenoid 52 (see FIG. 6) and energization of the solenoid 55 whereby the piston 31 may be rapidly advanced.

When the grinding wheel 10 has been advanced as far as is possible by the piston 31, this is indicated to the logic circuit by the actuation of the switch 73. Only after the switch 73 is actuated can the stepping motor 32 be moved to cause forward movement of the grinding wheel 10 toward the workpiece or part 15.

In the manual mode, only the coarse rate and rapid rate of movement of the stepping motor 32 are utilized and available for moving the grinding wheel 10. While the stepping motor 32 may be moved at medium and fine feed rates, these feed rates are not available in the manual mode. The stepping motor 32 is moved at the rapid rate, which is faster than the coarse rate, by actuating a rapid button 102.

When the manual select button 101 is actuated, the stepping motor 32 may be moved either in a forward or reverse direction through pushing a forward button 103 or a reverse button 104. Since the manual mode is used to set up the movement of the machine for the automatic modes of the present invention, the forward button 103 is normally moved initially. This sets the stepping motor 32 in a forward direction but the logic circuit does not permit actuation of the stepping motor 32 until the switch 73 has been actuated to indicate that the grinding wheel 10 is positioned for grinding; this is indicated in FIG. 8 by a block 105.

Thus, when the switch 73 has been actuated to indicate that the piston 31 has completed advance movement, then the stepping motor 32 may be moved at either the coarse rate or the rapid rate. A coarse rate square wave oscillator 106 is energized whenever the forward button 103 is pushed if the switch 73 has been actuated. The output of the square wave oscillator 106 is supplied through an amplifier 107 to the stepping motor 32 to cause the forward stepping of the stepping motor 32 at the coarse rate. When the rapid button 102 is actuated along with the forward button 103, the stepping motor 32 is advanced at a more rapid rate due to energization of a rapid rate square wave oscillator 108.

The stepping motor 32 remains energized by holding the forward button 103 actuated until the grinding wheel 10 has engaged the workpiece 15 sufficiently to clean up the workpiece or part 15 so that it may be measured for size. Then, a stock removal thumbwheel switch 109 has a desired amount of stock removal set thereon and on a stock removal number counter 110.

A cycle stop button 111 is then pushed to cause rapid retraction of the grinding wheel 10 away from the workpiece 15. This is accomplished through the button 111 causing deenergization of the solenoids 55 and 52 (see FIG. 6)

through the logic circuit. At the same time, the cycle stop button 111 causes the logic circuit to set the stepping motor 32 to run in the reverse direction, set in the stock removal distance from the switch 109, and run the stepping motor 32 at a frequency of a gap eliminator rate square wave oscillator 112 until the counter 110 reaches zero. Now the size of the workpiece 15 is determined and any additional required reduction in size of the workpiece is added to the stock removal switch 109. Thus, during an automatic mode, the stepping motor 32 is advanced from the selected reference position, which is where it is now positioned, not only the original amount that was placed on the stock removal switch 109 but also the amount that was added by the operator.

In the manual mode of operation, the coarse rate at which the stepping motor 32 is fed may be changed through movement of a coarse dial 113. This alters the output of the coarse rate square wave oscillator 106 through changing the value of a potentiometer in the oscillator 106.

After the stock removal switch 109 has had the desired amount of movement of the stepping motor 32 from its reference position, which has been selected due to the initial amount that the stepping motor 32 was backed off from the workpiece 15 after cleaning up the workpiece 15, registered thereon by the operator, automatic plunge grinding of the workpieces or parts 15 may be accomplished through utilizing the logic circuit of the present invention as indicated in FIGS.

9a and 9b. The total amount of movement of the stepping motor 32 from its reference position is indicated on the stock removal thumbwheel switch 109. Then, the operator determines when it is desired to change from coarse feed to medium feed and indicates this distance from the zero count position, which is zero count on the counter 110, on a medium feed thumbwheel switch 115. The distance through which the stepping motor 32 is advanced at a fine feed rate is indicated on a fine feed thumbwheel switch 116.

When it is desired to plunge grind the workpiece 15, a rate grind selector button 117 is pushed and released. This causes an automatic plunge grind cycle to occur in accordance with the logic circuit upon pushing the cycle start button 100.

When the cycle start button 100 is actuated, the piston 31 is advanced to rapidly move the grinding wheel 10 toward the workpiece 15. When forward movement of the grinding wheel 10 by the piston 31 has been completed, the switch 73 is actuated to indicate to the logic circuit completion of movement of the grinding wheel 10 by the piston 31. This results in the logic circuit causing the stepping motor 32 to be energized in a forward direction and to begin to advance the grinding wheel 10 toward the workpiece 15.

If a switch 118 is in its ON position, the gap eliminator square wave oscillator 112 is connected to the motor 32. Thus, the grinding wheel 10 is advanced at the gap eliminator rate until a surge switch (not shown) on the wheelhead 11 contacts the part or workpiece 15. As the stock removal counter 110 is down counted by pulses from the oscillator 112, each pulse also is sent to the stepping motor 32 to cause advancement of the stepping motor 32. This continues until the surge switch indicates that the grinding wheel 10 is in engagement with the workpiece 15.

At this time, the output of the gap eliminator square wave oscillator 112 is blocked from the counter 110 and the stepping motor 32, and the coarse rate square wave oscillator 106 has its output connected to the counter 110 and the stepping motor 32. This results in the oscillator 106 down-counting the stock removal counter 110 through supplying a pulse to the stock removal counter 110 and also to the amplifier 107 to cause the stepping motor 32 to step forward. The frequency at which the oscillator 106 supplies pulses is less than that at which the gap eliminator rate square wave oscillator 112 supplies pulses. The pulse rate of the oscillator 106 is determined through positioning the dial 113 as previously mentioned.

When the grinding wheel 10 has been advanced to the predetermined distance away from zero on the counter 110 as indicated on the medium feed thumbwheel switch 115, the output of the oscillator 106 is blocked from the counter 110 by the logic circuit, and a medium rate square wave oscillator 121 is connected to the counter 110 and the stepping motor 32 by the logic circuit. This results in the oscillator 121 supplying pulses to both the stock removal number counter 110 and the amplifier 107 to cause the stepping motor 32 to continue to advance the grinding wheel 10 toward the workpiece 15 at a slower feed rate. The pulse rate of the oscillator 121 is determined through positioning a medium rate dial 123. This varies the value of a potentiometer in the oscillator 121 to produce the desired feed rate of the grinding wheel 10 toward the workpiece or part 15.

When the grinding wheel 10 has been advanced to a point away from zero on the counter 110 as set on the fine feed thumbwheel switch 116, the output of the medium rate square wave oscillator 121 is blocked from the counter 110 and the motor 32 by the logic circuit, and a fine feed rate square wave oscillator 124 is connected to the counter 110 and the motor 32. This results in a lower pulse rate to the counter 110 and the motor 32 than when the medium square wave oscillator 121 was connected. As a result, the stepping motor 32 moves the grinding wheel 10 toward the workpiece 15 at a slower rate. The fine feed rate is determined through positioning a fine feed rate dial 125. This determines the frequency with which the oscillator 124 supplies its pulses by varying the value of a potentiometer in the oscillator 124.

It should be understood that the oscillator 124, rather than the oscillator 106, might be connected to the counter 110 and the motor 32 when the gap eliminator rate square wave oscillator 112 is blocked from the counter 110 due to a surge switch on the wheelhead 11 contacting the workpiece 15. This would occur if the surge switch should not be actuated until the grinding wheel 10 had been advanced by the stepping motor 32 from the reference position to at least a distance before zero count on the counter 110 equal to the distance indicated on the fine feed thumbwheel switch 116.

When the stock removal number counter 110 reaches zero, the grinding wheel 10 will have been fed into the workpiece 15 the entire total distance from its selected reference position that it is desired for it to be advanced into the workpiece 15.

At this time, the logic circuit receives a signal from the counter 110 to indicate that the counter is at zero. This automatically causes the logic circuit to again reset the number on the stock removal switch 109 and on the stock removal counter 110 and to reverse direction of the stepping motor 32.

If a reverse feed, which retracts the grinding wheel 10 a predetermined distance from the zero count position on the counter 110 before tarry or dwell occurs, is utilized, then the logic circuit also causes the gap eliminator rate square wave oscillator 112 to be connected to both a reverse feed number counter 127 and the stock removal number counter 110 after

the motor 32 is reversed by the logic circuit and the stock removal number counter 110 is again set with the total stock removal amount that is indicated on the switch 109. The reverse feed number counter 127 has the amount, which is on a reverse feed thumbwheel switch 129, supplied thereto only after the logic circuit has received a signal indicating that the stock removal number counter 110 had been down-counted to zero.

The oscillator 112 down-counts both the reverse feed number counter 127 and the stock removal number counter 110. Accordingly, the oscillator 112 causes the stepping motor 32 to retract the grinding wheel 10 from the workpiece 15 at its pulse rate.

When the reverse feed number counter 127 is down-counted to zero, the logic circuit causes energization of a tarry timer 130. Accordingly, the stepping motor 32 ceases to retract the grinding wheel 10 from the workpiece 15 for the time period set on the tarry timer 130. A selector dial 131 is utilized to set the time on the tarry timer 130. The amount of withdrawal of the grinding wheel 10 away from the workpiece 15 is such that the spring or windup in the system still causes the grinding wheel 10 and the workpiece 15 to remain in engagement with each other. Therefore, final finishing of the workpiece 15 is accomplished during the time that the grinding wheel 10 remains in engagement with the workpiece 15 in the position to which the grinding wheel 10 has been retracted by the motor 32 due to the oscillator 112.

When the tarry timer 130 times out, the rapid rate square wave oscillator 108 has its output connected to the counter 110 and the motor 32 by the logic circuit. This causes the stepping motor 32 to receive a pulse from the oscillator 108 each time that a pulse is supplied to the stock removal number counter 110 until the stock removal number counter 110 is down-counted to zero.

At the same time that the logic circuit causes the oscillator 108 to send pulses to the counter 110 and the motor 32 due to the tarry timer 130 timing out, it also causes retraction of the piston 31. As a result, the piston 31 rapidly retracts the grinding wheel 10 away from the workpiece 15. However, the stepping motor 32 continues to be driven until it returns to the reference position, which is the distance indicated on the stock removal switch 109. This reference position is reached when the stock removal number counter 110 is down-counted to zero.

If the reverse feed cycle were not utilized, the tarry timer 130 would be actuated by the logic circuit as soon as the direction of motion of the stepping motor 32 has been reversed by the logic circuit and the stock removal number counter 110 has again had the stock removal number, which is

on the stock removal thumbwheel switch 109, set therein. In the arrangement in which the reverse feed cycle is not utilized, the grinding wheel 10 is not removed from the position to which it has been advanced during fine feed but remains at this position for the time period determined by the setting of the tarry timer 130. Then, the oscillator 108 is connected to the counter 110 and the motor 32 to down-count the stock removal number counter 110 to zero and to cause the stepping motor 32 to be energized each time that a pulse is supplied to the stock removal number counter 110 from the oscillator 108. Of course, in the same manner as described for the reverse feed cycle, the piston 31 is rapidly retracted as soon as the tarry timer 130 has timed out.

As shown in FIG. 9a, there is a single cycle button 133 and a multicycle button 134. The multicycle button 134 can be utilized if the grinding machine is equipped with an automatic loading device. In the single-cycle mode, each grinding cycle of a particular workpiece or part must be initiated by pressing the cycle start button 100. However, in the multiple or continuous cycle mode, the logic circuit continues to recycle the grinding wheel 10 into the workpiece 15 after a signal has been received to indicate that a finished part has been unloaded and a new part has been loaded by the automatic loading device.

In the continuous cycle arrangement utilizing the automatic loading device, it is necessary to compensate for the wear of the grinding wheel 10. Otherwise, as the grinding wheel 10 wears, the advancement of the grinding wheel 10 from the reference position the distance on the stock removal switch 109 will not result in the grinding wheel 10 reducing the workpiece or part 15 to the same size. Accordingly, a wear compensation mechanism is utilized.

The wear compensation mechanism includes a wear compensation counter 135, which counts each time that one of the workpieces 15 is ground. Therefore, after a predetermined number of the workpieces 15 has been ground, the counter 135 supplies a signal to the logic circuit to prevent further continuous cycling of the automatic grinding machine of the present invention until wear compensation of the grinding wheel 10 has been made.

The wear compensation counter 135 causes the stock removal number counter 110 to have an amount set therein equal to the amount on a wear compensation thumbwheel switch 136. It also causes the stepping motor 32 to be set for movement in the forward direction. The logic circuit also causes the gap eliminator rate square wave oscillator 112 to be connected to the counter 110 and the motor 32 to supply pulses thereto. Thus, the motor 32 advances the grinding wheel 10 closer to the workpiece 15 by the distance set on the dial of the wear compensation switch 136.

When the stock removal number counter 110 has counted to zero, the gap eliminator rate square wave oscillator 112 is blocked from the counter 110 and the motor 32 to stop further movement of the grinding wheel 10. Furthermore, a signal is supplied from the logic circuit to allow another of the parts or workpieces 15 to be automatically loaded in the grinding machine of the present invention.

Thus, the utilization of the wear compensation means results in a new reference position being selected for the grinding wheel 10. However, because the grinding wheel 10 has been reduced in size due to wear, it still results in the workpiece 15 having the same finished size as when the prior reference position was employed.

It should be understood that the wear compensation counter 135 is returned to start counting from zero again upon starting the wear compensation cycle. This is accomplished automatically by the mechanism of the counter 135.

It also is necessary to true the grinding wheel 10 after a predetermined number of wear compensation cycles. Thus, a true compensation counter 137 is actuated after a predetermined number of the workpieces 15 have been ground by the grinding wheel 10. The counter 137 is not effective until the grinding wheel 10 has been returned to the reference position

from which another cycle could start, either automatically if the multicycle button 134 has been pushed or by pushing the single-cycle button 133. When the counter 137 indicates that it is time to true the grinding wheel 10, the logic circuit receives this signal from the wear compensation counter 135 since it also is actuated when the true compensation counter 137 is actuated and stops any further cycling until the truing cycle is completed.

When truing is to occur, the stock removal number counter 110 has the distance, which is on a compensation thumbwheel switch 138, supplied thereto. Furthermore, at this time, the motor 32 is set for forward movement.

Then, the output of the gap eliminator rate square wave oscillator 112 is connected to the motor 32 to advance the grinding wheel 10 toward the workpiece 15 the amount that will be removed from the grinding wheel 10 during truing; it also is connected to the counter 110 to down-count the counter 110 to zero. Accordingly, a new reference position for the grinding wheel 10 is again selected. It should be understood that the truing diamond moves with the grinding wheel 10 since it is mounted on the wheelhead 11. When truing, which is accomplished by an automatic truing mechanism supported on the wheelhead 11 after advancement of the grinding wheel 10 to a new reference position to compensate for both wear and removal of material from the grinding wheel 10 by the truing mechanism, has been completed, a signal is supplied to the logic circuit to indicate this.

It should be understood that the counter 137 is returned to start counting from zero upon starting the truing cycle. This is accomplished automatically by the mechanism of the counter 137.

While the plunge grind automatic cycle was described with utilizing the gap eliminator selector switch 118 in its ON position so as to utilize the gap eliminator rate square wave oscillator 112 for initial movement of the stepping motor 32, the switch 118 could be disposed in its OFF position. When this occurs, the initial energization of the stepping motor 32 occurs due to the coarse rate square wave oscillator 106.

Instead of utilizing predetermined distances, which have been selected by the operator, from the zero count position on the counter 110 to change the feed rate of the grinding wheel 10 into the workpiece 15, a gage, such as a jump-on gage, for example, may be utilized to change the feed rate of the grinding wheel 10 in accordance with the size of the workpiece 15. Thus, when the workpiece 15 reduces to a predetermined size as determined by the jump-on gage, the feed rate of the grinding wheel 10 may be reduced from coarse to fine. While the schematic diagram of FIGS. 10a to 10c discloses the gage controlling only a feed rate change from coarse to fine, it should be understood that the logic circuit could be designed so that the gage could control the changes of the feed rate from coarse to medium and from medium to fine.

When the grinding machine has the jump-on gage, pushing a gage grind selector button 140 and releasing it causes a gage grind cycle to occur. Thus, actuating the cycle start button 100 causes the piston 31 to be rapidly advanced to move the wheelhead 11 and the grinding wheel 10 toward the workpiece 15. When advancement of the grinding wheel 10 by the piston 31 has been completed, the limit switch 73 is actuated to indicate this to the logic circuit. Then, the logic circuit causes the number, which is on the stock removal thumbwheel switch 109, to be set in the stock removal counter 110.

With the gap eliminator selector switch 118 in its ON position, the grinding wheel 10 is advanced at the gap eliminator rate until the surge switch is actuated in the manner previously mentioned for the plunge grind cycle. Then, the stepping motor 32 advances the grinding wheel 10 at the coarse feed rate until the medium feed number has been reached on the stock removal counter 110. The medium feed number is the number on the medium feed thumbwheel switch 115.

When this occurs, the gage is advanced for positioning on the workpiece 15. However, the feed rate of the stepping motor 32 is not reduced at this time. Instead, the coarse rate

square wave oscillator 106 remains connected to the motor 32 and the counter 110 through the position of a switch 141 of a control 142 of the gage.

The grinding wheel 10 continues to be advanced by the stepping motor 32 at the coarse rate due to the oscillator 106. However, the oscillator 106 is no longer controlled by the logic circuit but is controlled by the switch 141.

When the switch 141 is moved by the gage sensing the size of the workpiece 15 reaching the size at which fine feed is to start, the coarse feed rate square wave oscillator 106 no longer is connected to the motor 32 and the counter 110. Instead, the fine feed rate square wave oscillator 124 is connected to the motor 32 and the counter 110. This results in the stepping motor 32 feeding the grinding wheel 10 into the workpiece 15 at the fine feed rate. Of course, the stock removal counter 110 continues to be down-counted.

When the size of the workpiece 15 is reduced to that at which it is desired to have dwell or tarry occur, a switch 143 in the gage control 142 moves to block the fine feed rate square wave oscillator 124 from the motor 32 and the counter 110 and energize the tarry timer 130. Then, the timer 130 continues to operate until it times out unless a switch 144 in the gage control 142 moves due to the size of the workpiece 15 reaching its desired size. If this occurs before the tarry timer 130 times out, then the tarry timer 130 is disconnected.

In either event, the remainder of the cycle is similar to that described for plunge grind control when there was no reverse feed cycle utilized. Of course, the gage also must be retracted when the grinding wheel 10 is moved back through the piston 31 and the stepping motor 32.

The gage grind automatic cycle may be either on the single-cycle or multiple-cycle arrangement in the same manner as described for the plunge grind control. Likewise, wear compensation and truing compensation along with automatic truing are accomplished in the same manner as described for the plunge grind control cycle.

It should be understood that the gage grind cycle is set up originally in the same manner as is the plunge grind control through utilizing the automatic grinding machine of the present invention in the manual mode. Of course, there is no utilization of the fine feed thumbwheel switch 116 in the gage grind control cycle because of the employment of the jump-on gage.

If a pickfeed grind cycle is desired rather than a plunge grind cycle, then a pickfeed grind selector button 150 (see FIG. 11a) must be actuated and then released. Then, when the cycle start button 100 is pushed, the piston 31 rapidly advances the grinding wheel 10 to the reference position.

With the grinding wheel 10 at the reference position, the logic circuit sets the stock removal number from the stock removal thumbwheel switch 109 on the stock removal counter 110. At the same time, the logic circuit causes a pickfeed increment number, which is on a pickfeed increment thumbwheel switch 151, to be set on a pickfeed increment counter 152.

If the gap eliminator selector switch 118 is in its ON position, the gap eliminator rate square wave oscillator 112 is connected by the logic circuit to the counter 110 and the motor 32 to cause down-counting of the stock removal counter 110 and advancement of the stepping motor 32. This continues until the surge switch indicates that the workpiece 15 has been engaged by the grinding wheel 10. At this time, the oscillator 112 is blocked from the motor 32 and the counter 110 by the logic circuit.

Then, advancement of the grinding wheel 10 does not proceed any further until the table 18 has actuated a limit switch at one of the ends of travel or movement of the table 18. These limit switches indicate reversal of the travel of the table 18 to the logic circuit.

When the limit switch for the table 18 is actuated to indicate that the direction of movement of the table 18 has been reversed, the gap eliminator rate square wave oscillator 112 is connected to the motor 32 and the counters 110 and 152 by

the logic circuit to cause the stepping motor 32 to advance the grinding wheel 10 into the workpiece 15 until the pickfeed increment counter 152 is down-counted by the pulses of the oscillator 112 to zero. When this occurs, the logic circuit stops further movement of the stepping motor 32 by the oscillator 112 through disconnecting the oscillator 112 from the motor 32 and the counters 110 and 152. It also causes the pickfeed increment counter 152 to again be reset with the number, which is on the pickfeed increment thumbwheel switch 151.

No further movement of the grinding wheel 10 occurs until the next time that one of the limit switches for the table 18 is actuated. When this occurs, the grinding wheel 10 is again advanced the desired pickfeed increment amount until the pickfeed increment counter 152 goes to zero. Then, the previously described stopping of the advancement of the stepping motor 32 and resetting of the pickfeed increment counter 152 occurs.

This continues until the stock removal counter 110 reaches zero. This may occur even though the pickfeed increment counter 152 is not at zero during one of the movements of the grinding wheel 10 further into the workpiece 15. However, further movement of the stepping motor 32 is stopped when the stock removal counter 110 goes to zero. When this occurs, further feeding of the grinding wheel 10 into the workpiece 15 is stopped.

Then, a dead pass table reversal counter 153 has the number, which is on a dead pass table reversal thumbwheel switch 154, set therein by the logic circuit. This causes the table 18 to be moved in reverse directions for the number of passes set on the switch 154 by the operator. The counter 153 is down-counted by each actuation of one of the limit switches for the table 18. When the counter 153 reaches zero, the logic circuit reverses the motor 32 and causes the piston 31 to be retracted. It also causes the stock removal number, which is on the stock removal thumbwheel switch 109, to be set in the stock removal counter 110. Thus, the retraction of the grinding wheel 10 by the piston 31 and starting of retraction of the grinding wheel 10 by the stepping motor 32 occur simultaneously.

The motor 32 is moved in the reverse direction by the rapid rate square wave oscillator 108. When the oscillator 108 has down-counted the stock removal counter 110 to zero, the oscillator 108 is blocked from the motor 32 and the counter 110 whereby movement of the stepping motor 32 is stopped. When this occurs, a signal is supplied to the logic circuit to indicate this. As a result, the workpiece 15 may be unloaded from the machine, either manually or automatically.

Instead of a single cycle, the multiple cycle arrangement may be utilized in the pickfeed grind cycle if the machine has an automatic part loader. Likewise, the wear compensation and truing compensation mechanisms are employed in the pickfeed grind cycle.

If the cycle stop button 111 should be actuated during a cycle because it is observed that the workpiece 15 is not being ground properly, the actuation of the cycle stop button 111 causes immediate retraction of the grinding wheel 10 away from the workpiece 15 through the piston 31. However, the stepping motor 32 continues to advance the grinding wheel 10 forwardly toward the workpiece 15, even though the grinding wheel 10 is now sufficiently removed from the workpiece 15 because of the retraction of the wheelhead 11 by the piston 31, through the gap eliminator rate square wave oscillator 112. The stepping motor 32 continues to advance inwardly until the stock removal counter 110 is down-counted to zero. Then, the reversal of the stepping motor 32 occurs for the distance set on the stock removal thumbwheel switch 109.

When the cycle stop button 111 is actuated to cause rapid reversal of the grinding wheel 10 away from the workpiece 15, the logic circuit prevents the number of reversals, which are on the dead pass table reversal switch 154, from being set on the dead pass table reversal counter 153.

The grinding machine of the present invention could be made so that only the pickfeed increment thumbwheel switch

151 of the various thumbwheel switches would be available for control by the operator. In this arrangement, the stock removal number, the various feed rates, wear compensation, true compensation, and reverse feed would be set. However, there would still be times when it might be necessary for the operator to advance the reference position a certain amount.

When this occurs, the operator could move the pickfeed increment switch 151 (see FIG. 8) to set the pickfeed counter 152 with the amount of movement set on the switch 151. Then, a manual pick button 155 would be actuated to move the motor 32 forward the amount set on the switch 151. Since the oscillator 112 is down-counting the pickfeed increment counter 152, forward movement of the grinding wheel 10 due to energization of the gap eliminator rate square wave oscillator 112 is stopped when the pickfeed counter 152 goes to zero even if the manual pick button 155 is still held down.

It should be understood that another manual pick button (not shown) could be utilized to move the motor 32 rearward. This would result in the motor 32 being moved in the reverse direction the amount set on the switch 151.

While the present invention has been shown and described as being utilized without a handwheel, it should be understood that a handwheel could be employed if desired. In such an arrangement, the handwheel would be connected to the worm 45c by extending the shaft 45a through the front base 20. If the motor 45 is retained, then the handwheel would be connected through the shaft 45a to the rapid motor 45. However, the handwheel would be connected to the shaft 45a through a clutch so that the handwheel does not rotate whenever the motor 45 rotates.

When the handwheel is utilized to position the grinding wheel 10, the operator must activate both the clutch, which connects the handwheel to the shaft 45a, and the clutch, which connects the shaft 45b to the feed screw 21 and includes the movable thin annular section 46d (see FIG. 7). When the grinding wheel 10 is positioned by the handwheel, the motor 45 freely turns.

If the motor 45 should not be employed and a handwheel should be used, then the handwheel would be directly connected to the worm 45c by the shaft 45a without any clutch connecting the handwheel to the shaft 45a. Then, it again is necessary to energize the clutch, which connects the shaft 45b to the feed screw 21, in order for the handwheel to be able to position the grinding wheel 10.

Accordingly, while the present invention preferably eliminates any manual handwheel, it is readily adaptable for use with a manual handwheel if such is desired. Furthermore, the motor 45 may be either utilized in conjunction with the handwheel or omitted.

While the present invention has shown and described the grinding wheel 10 as being movable toward and away from the workpiece 15, it should be understood that this invention could be employed in a grinding machine in which the workpiece is moved toward and away from the grinding wheel. Thus, it is only necessary for there to be relative movement toward and away from each other between the grinding wheel and the workpiece.

It should be understood that the pickfeed mode could be employed with the gage controlled mode if desired. In this arrangement, the pickfeed mode would be controlling except that the gage would determine when the workpiece had been reduced to the final size. Additionally, the gage could be used to determine when to change feed rates and/or increments of pickfeed in accordance with the size of the workpiece.

An advantage of this invention is that substantially uniform products may be automatically ground. Another advantage of this invention is that various workpiece support tables may be readily utilized with the infeed mechanism of the present invention. A further advantage of this invention is that a compact infeed mechanism for a grinding machine is provided.

For purposes of exemplification, a particular embodiment of the invention has been shown and described according to the best present understanding thereof. However, it will be ap-

parent that changes and modifications in the arrangement and construction of the parts thereof may be resorted to without departing from the spirit and scope of the invention.

What we claim is:

5 1. A mechanism for producing relative movement toward and away from each other between a tool of a machine tool and a workpiece comprising:

a feed member;

fluid-responsive means including:

a housing having a chamber therein;

and a piston disposed in said chamber in said housing to produce relative translational movement between said housing and said piston when fluid is supplied to said chamber;

said piston having means to rotatably support said feed member;

first means connecting said piston to said feed member; said first connecting means including motive means to rotate said feed member relative to said fluid-responsive means; means to prevent relative rotation between said motive means and said housing;

said means to connect one of said feed member and said housing to the movable one of the workpiece and the tool and to connect the other of said feed member and said housing to a fixed structure;

and said second connecting means including means to convert rotational movement of said feed member to translational movement of the movable one of the workpiece and the tool;

said motive means rotating said feed member both independently of movement of the movable one of said piston and said housing due to fluid supplied to said chamber and simultaneously therewith.

2. The mechanism according to claim 1 including means to regulate the rate of movement of said fluid-responsive means.

3. The mechanism according to claim 1 in which:

said fluid-responsive means and said motive means are mounted concentrically with said feed member; and said fluid-responsive means is in surrounding relation to a portion of said feed member.

4. The mechanism according to claim 1 in which said motive means is a stepping motor.

5. The mechanism according to claim 1 in which:

said second connecting means includes:

means to connect said feed member to the movable one of the workpiece and the tool;

and means to connect said housing to the fixed structure; and said feed member both rotates and translates simultaneously or independently to impart movement to the movable one of the workpiece and the tool.

6. The mechanism according to claim 5 including:

drive means adapted to be connected to said feed member for moving said feed member independently of said motive means and said fluid-responsive means;

and means to selectively connect said drive means to said feed member, said drive means moving said feed member at a faster rate than said motive means but a slower rate than said fluid-responsive means.

7. A mechanism for controlling the grinding of a workpiece by a grinding wheel including:

mean to feed one of the grinding wheel and the workpiece toward the other whereby the one of the grinding wheel and the workpiece is a movable member and the other of the grinding wheel and the workpiece is a fixed member, said feed means feeding the movable member for a predetermined distance from a reference position;

means to automatically stop feeding by said feed means when the movable member has been advanced toward the fixed member the predetermined distance from the reference position;

means to retract the movable member a predetermined distance after said stop means is actuated, the grinding wheel and the workpiece remaining in engagement with

- each other in the retracted position of the movable member;
and means to hold the movable member at the retracted position for a predetermined period of time.
8. The mechanism according to claim 7 including means to move the reference position a predetermined distance closer to the fixed member after a predetermined number of the workpieces has been ground.
9. The mechanism according to claim 7 including means to rapidly move the movable member to the reference position.
10. The mechanism according to claim 7 including means to vary the predetermined distance that said retracting means retracts the movable member.
11. The mechanism according to claim 7 including means to vary the predetermined period of time during which said holding means is effective.
12. The mechanism according to claim 7 in which:
said feed means comprises:
motive means;
and speed-reducing means.
13. The mechanism according to claim 12 in which said motive means is a stepping motor.
14. A mechanism for controlling the grinding of a workpiece by a grinding wheel including:
means to feed one of the grinding wheel and the workpiece toward the other whereby the one of the grinding wheel and the workpiece is a movable member and the other of the grinding wheel and the workpiece is a fixed member,
said feed means feeding the movable member from a reference position;
means to measure the size of the workpiece being ground;
said measuring means having means to reduce the feed rate of said feed means when the workpiece has been reduced to a predetermined size by the grinding wheel as determined by said measuring means;
means to stop feeding of the movable member by said feed means when the workpiece has further been reduced by the grinding wheel as determined by said measuring means;

- means to retract the movable member a predetermined distance after said stop means is actuated, the grinding wheel and the workpiece remaining in engagement with each other in the retracted position;
and means to hold the movable member at the retracted position for a predetermined period of time.
15. The mechanism according to claim 14 including means to vary the predetermined period of time during which said hold means is effective.
16. The mechanism according to claim 5 in which said means connecting said feed member to the movable one of the workpiece and the tool includes means to simultaneously transfer the translation and rotational movement of said feed member to translational movement of the movable one of the workpiece and the tool.
17. The mechanism according to claim 1 in which:
said motive means is connected to said piston;
said first connecting means includes means connecting said motive means to said feed member;
- 20 and said preventing means prevents rotation of said motive means and said piston relative to said housing when said motive means is activated.
18. The mechanism according to claim 17 in which said connecting means connecting said motive means to said feed member includes speed-reducing means.
19. The mechanism according to claim 1 in which said motive means comprises means to rotate said feed member in either direction.
20. The mechanism according to claim 19 including means to limit the rotation of said feed member in either direction by said motive means in accordance with the relative position between the workpiece and the tool.
21. The mechanism according to claim 1 including means to selectively change the rate of rotation of said feed member by said motive means during movement of the movable one of the workpiece and the tool.
22. The mechanism according to claim 1 including means to selectively control the amount of relative translational movement between said housing and said piston.

UNITED STATES PATENT OFFICE
CERTIFICATE OF CORRECTION

Patent No. 3,599,376 Dated August 17, 1971

Inventor(s) Howard W. Renner et al.

It is certified that error appears in the above-identified patent and that said Letters Patent are hereby corrected as shown below:

IN THE ABSTRACT

Line 7, cancel "to"

IN THE SPECIFICATION

Col. 2, line 2, after "Therefore" insert a---comma (,)---

Col. 4, line 11, cancel the "hyphen (-)"

line 13, cancel the "hyphen (-)"

line 26, after "wheel" insert---10---

Col. 5, line 5, "n" should be---on---

Col. 6, line 14, "form" should be---from---

Col. 7, line 28, "setscrew" should be---set screw---

line 40, after "motor" insert---32---

Col. 9, line 58, after "medium" insert---feed---

Col. 11, line 16, "multicycle" (both occurrences) should be
--- multi-cycle ---

line 18, cancel the "hyphen (-)"

Col. 12, line 2, "multicycle" should be--- multi-cycle ---

line 3, cancel the "hyphen (-)"

Col. 13, line 32, cancel the "hyphen (-)"

line 33, cancel the "hyphen (-)"

UNITED STATES PATENT OFFICE
CERTIFICATE OF CORRECTION

Patent No. 3,599,376 Dated August 17, 1971
Inventor(s) Howard W. Renner et al. PAGE - 2

It is certified that error appears in the above-identified patent and that said Letters Patent are hereby corrected as shown below:

IN THE CLAIMS

Col. 16, line 23, "said" (first occurrence) should be
---second---

Col. 17, line 20, cancel the "hyphen (-)"

Col. 18, line 25, cancel the "hyphen (-)"

Signed and sealed this 25th day of July 1972.
